ROTARY RECEPTACLE CLOSURE

James R. McGrath, Wildwood, N. J.

Application April 28, 1947; Serial No. 744,296

2 Claims. (Cl. 222—507)

1

This invention relates to a rotary closure especially designed for use in connection with collapsible metal tubes in which various paste-like commodities are sold.

More particularly, the present invention relates to that type of closure embodying a revolving or rotary spherical closure member actuated by a rotatable cap member of a socket element in which the spherical closure member is mounted.

The primary object of the present invention is to generally simplify and improve the detailed construction of closures of the above kind.

The exact nature of the present invention will become apparent from the following description when considered in connection with the accompanying drawing, in which:

Figure 1 is a vertical sectional view of a closure constructed in accordance with the present invention and applied to the neck of a collapsible tube, the closure member being in open position.

Figure 2 is a vertical sectional view taken on line 2—2 of Figure 1.

Figure 3 is a horizontal section taken on line 3—3 of Figure 1.

Figure 4 is a horizontal section taken on line 4—4 of Figure 1.

Figure 5 is a perspective view of the closure member forming part of the closure shown in Figure 1.

Figure 6 is a bottom plan view of the closure, per se, showing a modification.

Figure 7 is an elevational view, partly broken away and in section, showing the closure of Figure 6 applied to the neck of a collapsible tube.

Figure 8 is an enlarged fragmentary vertical section taken on the line 8—8 of Figure 6.

Referring in detail to the drawing, the present closure includes a socket element which comprises a circular base member 5 having a central opening 6 at the bottom and formed in the top and about the opening 6 with a segmento-spherical seat 7 and an arcuate rabbet 8 around a portion of and at the top of the seat 7. The base member 5 has an arcuate series of rack teeth 9 on the bottom of the rabbet 8. The socket element further comprises a flanged cap member 10 rotatably fitted and secured on the base member 5 and having a central opening 11 at the top and formed in the bottom and about the opening 11 with a segmento-spherical seat 12 coacting with the seat 7 to form a substantially spherical socket. The cap member 10 is formed in the bottom of its top wall at opposite sides of the seat 12 with diametrically opposed bear-

2

ing recesses 13. The base member 5 may be formed integral with the neck 14 of the receptacle or collapsible tube 15, but, as shown, it has a depending internally threaded marginal flange 15 adapted to be screwed on the externally threaded neck of a conventional collapsible tube. When the latter is the case, the user may employ the closure on successive collapsible tubes in lieu of the conventional closure cap provided on the neck thereof. The cap member 10 has a depending marginal flange 16 which fits about the base member 5 and preferably extends to the bottom of the latter. In the form shown in Figures 1 to 5 inclusive, the flanges 15 and 16 have mating internal annular grooves which receive a spring retaining ring 17 for removably securing the cap member 10 on the base member 5. This is a common expedient which is well-known and needs no more detailed description herein.

20 A rotary spherical closure member 18 is fitted in the socket formed by the seats 7 and 12, and this closure member has a diametric passage 19 therethrough. Also, the closure member 18 is provided at opposite sides with diametrically opposed stub shafts 20 which project at right angles to the passage 19 and are journaled in the bearing recess 13 of the cap member 10. One of the stub shafts 20 has gear teeth 21 which may form a complete gear or a gear sector and which are arranged to mesh with the rack teeth 9 of base member 5. The arrangement is such that the cap member 10 is held by the retaining ring 17 with its top wall in snug contact with the top of base member 5 and with the seats 7 and 12 in snug contact with the external surface of the closure member 18. Further, rotation of the cap member 10 relative to the base member 5 in reverse directions will cause rotation of the closure member 18 about the axes of the stub shafts 20 due to engagement of the gear teeth 21 with the rack teeth 9, and about the axis of the passage 19 due to engagement of stub shafts 20 in the bearing recesses 13 of cap member 10. Such rotation of the cap member in reverse directions will respectively cause the passage 19 to align with the openings 6 and 11 as shown and to position the passage 19 out of alignment with said openings 6 and 11 to respectively open or close the closure. As the openings 6 and 11 are aligned with the passage through the neck 14 of the receptacle or collapsible tube 15, the closure member 18 will naturally serve to either permit the contents of the receptacle to be dispensed or to close the outlet of the receptacle

when dispensing of the contents of the receptacle is not desired.

In the embodiment of Figures 6 to 8 inclusive, the flange 15 of the base member 5 is provided at the bottom and at opposite sides with arcuate rabbets 22, and the flange or rim 16 of the cap member 10 is provided at opposite sides with inwardly projecting lugs 23 which project into the rabbets 22. The top or horizontal walls of the rabbets 22 are inclined so as to have a camming action on the lugs 23 and thereby cause the cap member 10 to be drawn downwardly as said cap member is turned in a direction to shift the closure member 18 to closed position. This insures very snug engagement of the parts 5, 10 and 18 with each other to effectively exclude air from the receptacle 15 when closed and to prevent accidental expulsion of the contents from the receptacle at such time. As the lugs 23 retain the cap member 10 on the base member 5, they supplant the retaining ring 17 of the form of the invention shown in Figures 1 to 5 inclusive. Otherwise, both forms are similar in construction, and like parts of both forms are indicated by corresponding characters. However, it is noted that the flange 16 in the form of Figures 6 to 8 inclusive is preferably longitudinally slotted upwardly from its lower edge as indicated so that the flange or rim 16 is composed of yieldable resilient sections that may expand to permit assembly of the cap member to the base member, the lugs 23 snapping into the rabbets 22 when the parts are completely assembled.

An advantage of the present construction is that the parts 5 and 10 may be readily cast in the desired form to provide parts which are relatively thick and durable. This is a decided advantage over prior constructions in which the cap member has been formed of thin sheet metal and made by a spinning or stamping operation. By the use of the retaining ring 17 or the lugs 23 engaged in rabbets 22 at the bottom of the flange 15 of the base member, there is no need to provide the base member with a top flange or with top and bottom flanges as heretofore proposed. Still further, provision of the rabbet 8 with the rack teeth 9 therein provides for a construction in which a continuous annular flat face is provided at the top of the base member 5 for contact with a similar surface of the cap member 10.

From the foregoing description, it is believed that the construction, operation and advantages of the present invention will be readily understood and appreciated by those skilled in the art.

What I claim is:

1. A rotary receptacle closure comprising a socket element, said socket element including a cylindrical base member having a central opening whose wall forms a segmento-spherical seat, said base member having an arcuate rabbet in the top thereof around a portion of and at the top of said seat, said rabbet defining a bottom wall and a vertical wall at the outer side of said bottom wall inwardly of the periphery of the base member, said base member having an ar-

cuate series of rack teeth on the bottom wall of said rabbet, and a flanged cap member rotatably fitted and secured on said base member and having a thick top portion provided with a central opening whose wall forms a segmento-spherical seat extending to the bottom of said top portion and co-acting with the first named seat to form a substantially spherical socket, said cap member being formed in the bottom of its top wall and at opposite sides of the second named seat with diametrically opposed bearing recesses and with a larger recess at the inner end of one of said bearing recesses, and a rotary spherical closure member fitted in said socket, said closure member having a diametrical passage therethrough and being provided at opposite sides with diametrically opposed stub shafts which project at right angles to said passage and are journaled in said bearing recesses, one of said stub shafts having a gear on its inner end arranged in said larger recess and meshing with said rack teeth whereby rotation of the cap member in reverse directions will cause rotation of the closure member about the axes of said stub shafts and about the axis of said passage to respectively align said passage with said openings and to position said passage out of alignment with said openings, the base member having a depending internally threaded marginal flange adapted to be screwed on the externally threaded neck of a collapsible receptacle, said cap member having a cylindrical depending marginal flange extending to the bottom of the depending flange of said base member and completely enclosing the cylindrical surface of the latter, and means coacting with the flanges of the base member and the cap member for rotatably retaining the latter on said base member.

2. The construction defined in claim 1, wherein in the depending flange of the base member has an external rabbet in the lower edge thereof, the depending flange of said cap member being provided at its lower edge with an inwardly directed lug projecting into said rabbet, the top wall of said rabbet being inclined to have a camming action on said lug for drawing the cap member and the closure member into snug engagement with each other and the base member when the cap member is rotated to move the closure member to closing position.
